UNITED STATES PATENT OFFICE.

WILLIAM C. F. BRUEGEMANN, OF ST. LOUIS, MISSOURI.

ROTARY ENGINE.

1,249,896.

Specification of Letters Patent. Patented Dec. 11, 1917.

Application filed June 8, 1915. Serial No. 31,991.

To all whom it may concern:

Be it known that I, WILLIAM C. F. BRUEGEMANN, a citizen of the United States, residing at 4316 N. 20th street, in the city of St. Louis and State of Missouri, have invented certain new and useful Improvements in Rotary Engines, of which the following, taken in connection with the accompanying drawings, is a specification.

This invention relates to improvements in rotary engines of the kind in which the actuating fluid is admitted in a continuous manner into the working chamber thereof to do work and the objects of my improvements are; first, to construct engines of this kind which are adapted to be operated by actuating fluid which flows through an expanding nozzle or passage from which said fluid enters the working chamber of the engine in a continuous manner to do work; and, to operate the engines so that normally the actuating fluid does work in the working chamber thereof at a lower pressure than the initial pressure of said fluid, so that normally the actuating fluid is expanded in said expanding nozzle or passage from an initial to a lower working pressure; second, to construct engines of this kind to be reversible and adapted to be operated, shut down, or reversed in a simple manner by means whereby the flow of the actuating fluid into the working chamber thereof may be controlled; third, to obtain a perfectly balanced engine which has no dead point and is of a simple and durable construction, the parts of which are adjustable for wear, and may be effectively lubricated, these and other objects are accomplished by the engine hereinafter described.

The invention consists in certain features of construction hereinafter described and pointed out in the claims.

Reference is to be had to the accompanying drawings forming a part of this specification, in which similar characters of reference indicate corresponding parts in all the figures.

In the drawings which illustrate this invention, Figure 1 is an elevation showing the inlet side of an engine embodying my improvements; Fig. 2 is an elevation of the engine at right angles to Fig. 1, in which the inlet side is shown to the right of the figure; Fig. 3 is a side elevation of a thin plate; Figs. 4 to 6 inclusive are illustrative sections through oscillatory pistons, (to be

referred to later) in which a dotted outline indicates the position of a crank thereon; Fig. 7 is a sectional elevation of the engine at right angles to Figs. 2 and 8 as seen from the inlet side thereof, in which the section through a revolving cylinder is on line C—D, and through a cam-ring on line E—F of Fig. 2; Fig. 8 is a longitudinal section through the engine at right angles to Fig. 1 on line A—B thereof, in which the inlet side is shown to the right of the figure; Fig. 9 is a side elevation of the hollow stationary shaft or cylinder of the engine; Figs. 10 and 11 are part sections through said hollow stationary shaft or cylinder to be referred to later; Figs. 12, 13 and 14 show respectively an inside elevation, edge view, and section (on line Q—R of Fig. 12) of the half cylinder shown in Fig. 7; Figs. 15 and 16 show respectively a plan and side elevation of bearing sleeves; Figs. 17, 18 and 19 show respectively a plan, elevation, and section (on line S—T of Fig. 17) of oscillatory pistons; Fig. 20 is a top view of a crank, shown mounted on an oscillatory piston; Figs. 21 and 22 are elevations of a valve, a cross section of which is shown in Fig. 7; Figs. 23, 24 and 25 are part sections which illustrate a modified construction of the hollow stationary shaft and valve shown in previous figures; Figs. 26 and 27 are elevations of the modified valve in this construction.

Referring to the drawings, as shown in Figs. 1, 2 and 8 a hollow stationary shaft or cylinder 1 having an inlet 2 and an exhaust head 3 secured to the ends thereof, is supported by upright stands 4 and forms therewith the frame of the engine resting on a bed-plate 5, the heads 2 and 3 being mounted adjustably on seats 6 which are formed on stands 4.

A revolving cylinder 7 provided with the oscillatory division members or pistons 8 and 9 is mounted on the hollow stationary shaft 1, and rotates on tapered bearing sleeves 10 provided on said shaft 1. Revolving cylinder 7 is constructed in halves which are adapted to be held concentric when bolted together, as shown in Fig. 8. The walls of the half cylinders form circular cavities 11 and 12, and the diametrically opposite radial piston seats 13, at the outer end of which the flange 14 is provided, as shown in Figs. 12, 13 and 14.

Centrally located, on the outside of the

hollow stationary shaft 1, a projecting collar 15 is formed (see Figs. 7, 8 and 9) the periphery of which is shaped as the central section of a sphere, the width thereof being equal to the diameter of the pistons 8 and 9. A vane or abutment 16 projects from collar 15 the radial edges of which (Fig. 7) are approximately sixty degrees apart.

In Figs. 7 and 8 sections through revolving cylinder 7 mounted on hollow stationary shaft 1 are shown; as will be seen the projecting collar 15 is partly included in and fitted closely to the walls of cavities 12, the vane or abutment 16 projects vertically downward from collar 15 into cavities 11, and is fitted closely between the walls thereof, where so included, the walls of cavities 11, the radial edges of vane or abutment 16, and the exposed portion of the periphery of collar 15 form the annular working chamber 11 of the engine.

The construction of the identical oscillatory division members or pistons 8 and 9 is shown in Figs. 17, 18 and 19; as will be seen a central slot 17 is formed between diametrically opposite piston wings 18 which are connected at one end, from which a round stem 19 extends having a square seat 20 at the end thereof. In Fig. 7 the pistons 8 and 9 are shown mounted in the diametrically opposite piston seats 13, the axis thereof being located in the central plane of revolving cylinder 7 and of collar 15. These pistons have a diameter approximately three times the width of working chamber 11. The inner end 21 of the piston wings 18 is concaved to fit the spherical periphery of collar 15 so as to be adapted to be in fluid tight contact therewith in any position of pistons 8 and 9 in seats 13. The pistons are provided with identical cranks 22 which are mounted on seats 20 and held at an angle of thirty degrees with slot 17 (Fig. 20), being secured to stem 19 by the set-screws 23. Rollers 24 are mounted on the cranks 22 and held thereon by the collared pins 25. The rollers 24 are adapted to project into and travel in a cam-path 26, which is formed between the inwardly projecting flanges 27 of the cam-ring 28, and is held concentric with revolving cylinder 7 by stands 29 on the lower half which are secured to bed-plate 5. As pistons 8 and 9 rotate in either direction with revolving cylinder 7 the flanges 27 of cam-ring 28 (through rollers 24 and cranks 22) control the position of slot 17 in relation to working chamber 11 in the following manner. As shown in Figs. 1, 2, 7 and 8, in the lower half of cam-ring 28 between points 30—31, the cam-path 26 is offset from the central plane of revolving cylinder 7 toward the inlet side of the engine, and as rollers 24 travel between said points 30—31 the slot 17 of piston 8 or 9 is held in

alignment with working chamber 11; in this position piston wings 18 form a continuation of the walls of working chamber 11 as pistons 8 or 9 pass vane or abutment 16, as is illustrated in Fig. 6, in which a cross section through piston wings 18 in piston seats 13 is shown, the section through vane or abutment 16 being taken on line K—L of Fig. 1. Between points 32—33 in the upper half of cam-ring 28, the cam-path 26 is offset (an equal distance from said plane) toward the opposite or exhaust side of the engine; in the offset parts the center of cam-path 26 is at a distance from said plane which is equal to the distance of the axis of rollers 24 from the axis of pistons 8 or 9; consequently, as rollers 24 travel between points 32—33 in the upper offset cam-path 26, the slot 17 of the piston 8 or 9 will be held at an angle of sixty degrees with working chamber 11 during a half revolution of revolving cylinder 7. In this position (Figs. 4 and 5) the piston wings 18 will be seated across working chamber 11, and will be adapted to form fluid tight walls in seats 13 which divide working chamber 11 into compartments, whereby piston wings 18 are adapted to act as piston abutments to propel revolving cylinder 7 in either direction. Figs. 4 and 5 are cross-sections through piston seats 13 and pistons 8 and 9 respectively on lines G—H and I—J of Fig. 1; the sections are shown as they would be seen when viewed from a position facing Fig. 2. Between points 30—32 and 31—33, in the lower half of cam-ring 28, the cam-path 26 is inclined (to said plane) and joins the offset parts thereof with short curves, so that as rollers 24 travel through an inclined part of cam-path 26 the piston 8 or 9 will be oscillated through an angle of sixty degrees in seats 13. I prefer to oscillate the pistons this angle as best suited to the smooth running of rollers 24 in cam-path 26. Revolving cylinder 7 through hollow shaft 1 and heads 2 and 3 is adjustable in relation to cam-ring 28 by means of the set screws 34, which will be understood by reference to Figs. 1, 2 and 8.

Circular flanged retaining sleeves 35 are fitted into the outer end of piston seats 13 and are secured to flanges 14, as shown in Figs. 1, 2, 7 and 8. The inner sleeves 36 are rotatably connected with sleeves 35 by means of the threaded shoulders 37; the stem 19 of pistons 8 and 9 extends through a central hole formed in sleeves 36 and fits loosely therein; a thin washer (not shown) is placed between sleeves 36 and the shoulders of pistons 8 and 9. As will be seen sleeves 36 may be rotated by means of notches 38 so as to travel toward or away from piston 8 or 9 whereby the concaved end 21 of piston wings 18 may be held in contact with the spherical periphery of collar 15 as closely as de-

sired, and wear taken up. The flanged glands 39 project into cavity 40 between sleeves 35 and 36 and are adapted to compress packing against the threaded shoulders 37, which prevents leakage and also tends to lock sleeves 36. The glands 39 are secured to flanges 14 by two bolts 41 which also pass through the flange of sleeves 35.

The tapered bearing sleeves 10 are mounted on hollow shaft 1 with a sliding fit and extend into the tapered bore of hubs 42 of revolving cylinder 7. Sleeves 10 are provided with lugs 43 through which the setscrews 44 are threaded so that the ends thereof project into a shallow recess 45 and are also adapted to press therein against the lugs 46 (Figs. 1 and 2) which are formed on the heads 2 and 3; by these means sleeves 10 may be held fluid tight in hubs 42 and adjusted for wear. The diameter of hollow shaft 1 is slightly increased at each side of collar 15, to form the short inclines 47, which are of such dimensions that setscrews 44 may force the thin end of sleeves 10 over said inclines 47 to produce a fluid tight fit thereon between sleeves 10 and hollow shaft 1. Setscrews 48 assist in securing sleeves 10. The bearing sleeves 10, working chamber 11, and piston seats 13 may be lubricated by oil under pressure from the oil duct 49 (Fig. 8) which extends through the lower part of inlet head 2 into hollow shaft 1 and has two downwardly extending branches with openings in the sides of collar 15.

The bore of hollow shaft 1 is divided into an inlet 50 and an exhaust chamber 51 by the tapered or cone shaped valve 52 which is seated rotatably and fluid tight in the projecting valve seat 53, formed centrally in said bore, (Fig. 8) the smaller end of valve 52 facing inlet chamber 50. An inlet 54 and exhaust pipe 55 may be supported on and secured to the respective heads 2 and 3 to communicate with the respective chambers 50 and 51 through openings formed in said heads 2 and 3.

The tapered valve 52 is secured on the round valve rod 56 which extends through a stuffing box 57 formed on inlet head 2 which is made fluid tight in the usual manner by the gland 58. A lever 59 is loosely mounted on valve rod 56 the hub of which is held in contact with the gland 58 by the nut 60 threaded on the valve rod 56. A setscrew 61 threaded through the hub of lever 59 is adapted to extend into and be in contact with the sides only of a short slot 62 (Fig. 8) formed in valve rod 56; in this manner means are provided to rotate and adjust valve 52 in valve seat 53. The circular cover 63 is removable from exhaust head 3, allowing the removal of valve 52 when necessary.

An expanding inlet port 64 (Fig. 21) is formed lengthwise in the periphery of tapered valve 52. This port 64, in conjunction

with the tapered valve seat 53, is adapted to form a passage or nozzle having a gradually increasing cross-section, beginning at the small rounded throat 65 thereof which is in communication with inlet chamber 50 (Figs. 8 and 10). As will be seen this passage or nozzle 64, is similar to and is adapted to expand the actuating fluid therein, as in the expanding nozzle of a turbine, from an initial to a lower pressure. Circular ports 66 and 67 are formed through collar 15 at each radial edge of vane or abutment 16. The large end of expanding inlet port 64 is adapted to register with ports 66 and 67, and when in register with either port 66 or 67 an inlet passage is formed through which the actuating fluid may flow from inlet chamber 50 into working chamber 11, as illustrated in Fig. 10; this section is at right angles to and on line M—N of Fig. 7 and is shown as viewed from letter O, showing port 64 in register with port 66.

Two identical exhaust ports 68 and 69 (Fig. 22) formed in the periphery of valve 52 are also adapted to register with ports 66 and 67 to form therewith identical exhaust passages from working chamber 11 into exhaust chamber 51. Said ports 68 and 69 are spaced on either side of expanding inlet port 64 (Fig. 7) so that when port 64 is in register with port 66 the exhaust port 69 will be in register with port 67; when port 64 is in register with port 67 then exhaust port 68 will be in register with port 66. An exhaust passage is illustrated in Fig. 11, this section is at right angles to and on line O—P of Fig. 7 and is shown as viewed from the letter M, showing exhaust port 69 in register with port 67. The cross-sectional contour of ports 64, 68, and 69 is shown semi-circular but may be otherwise. The expanding inlet port 64 could also be constructed as a round nozzle entirely within the body of tapered valve 52 but would necessitate an increased diameter of hollow shaft 1; I therefore prefer the construction shown.

The part sections Figs. 23, 24, and 25 illustrate a modified construction of hollow shaft 1 in which valve seat 53 is adapted to seat a longer tapered valve 52 (Figs. 26 and 27) having a longer expanding inlet port 64. As will be understood the dimensions of said port 64 are determined by the normal conditions of pressure load and so forth for which the engines are designed. When necessary the ports 66 and 67 may be enlarged as shown in Fig. 23; likewise the exhaust ports 68 and 69 (Fig. 27). The Figs. 24 and 25 are part sections at right angles to and on lines U—V and W—X respectively of Fig. 23, showing an inlet and exhaust passage respectively in this construction.

The operation of the engine is as follows;

in the position shown in Fig. 7 it will be seen that piston wings 18 are seated across working chamber 11, the inlet passage is formed by port 64 in register with port 66, 5 the exhaust passage by port 69 in register with port 67; consequently, steam under pressure as the actuating fluid having entered inlet chamber 50 from inlet pipe 54, will flow through the inlet passage (ports 10 64 and 66) into working chamber 11 between vane or abutment 16 and piston 8. The pressure of the steam on piston 8 propels this piston toward the exhaust passage (ports 69 and 67) and rotates revolving cylinder 7 in the direction indicated by the 15 arrows, the contents of working chamber 11 on the advancing side of piston 8 escaping through the exhaust passage into exhaust chamber 51. Piston 8 propels revolving cylinder 7 (a half revolution) until arrived at the position before held by piston 9, the 20 roller 24 thereof having traveled in the upper offset cam-path 26 from point 32 to 33. In the meantime, piston 9 while approaching 25 vane or abutment 16 is oscillated through an angle of sixty degrees as the roller 24 thereof travels from point 33 through this inclined part of cam-path 26 to point 31, whereby slot 17 is brought into alinement 30 with working chamber 11; continuing in this position piston 9 passes vane or abutment 16, as roller 24 travels from point 31 through the lower offset cam-path 26 to point 30; having passed vane or abutment 16 piston 35 9 is again oscillated through an angle of sixty degrees, as roller 24 travels from point 30 through this inclined part of cam-path 26 to point 32, arrived at which, the piston 9 will occupy the position before held 40 by piston 8 and with piston wings 18 again seated across working chamber 11. Piston 9 is now acted on by the steam and propels revolving cylinder 7 a half revolution during which the roller 24 thereof travels from 45 point 32 to point 33, and the steam which propelled piston 8 is exhausted into exhaust chamber 51. While piston 9 propels revolving cylinder 7 the piston 8 is oscillated as has been described for piston 9, and as the 50 pistons arrive at the original position a complete revolution of revolving cylinder 7 has taken place.

In order to rotate revolving cylinder 7 in a direction opposite to that indicated by the 55 arrows of Fig. 7, the valve 52 is rotated by means of lever 59 so that port 64 will be in register with port 67, in which case exhaust port 68 will be in register with port 66.

In order to operate the engine with actuating fluid at a low pressure in working chamber 11 the exhaust ports 68 and 69 and ports 66 and 67 should have the largest possible cross-section, to reduce back pressure in working chamber 11. In an ideal 60 engine the cross-section of the exhaust port

would be equal to the cross-section of the working chamber; then the actuating fluid could be employed in the working chamber at a pressure slightly above that of the atmosphere or of a condenser into which the 70 engine exhausts.

By expanding the actuating fluid in the expanding passage or nozzle 64 from an initial to a lower pressure, said fluid is enabled to flow at great speed into working 75 chamber 11, to maintain a constant low pressure on pistons 8 or 9 when the load allows revolving cylinder 7 to rotate at high speed. In this manner considerable power may be developed in a small unit, and at the low 80 pressure fluid tightness is easily had.

The drawings show a convenient construction whereby power may be transmitted from revolving cylinder 7 to a shaft 70 by means of pulleys 71 and belt 72; this construction, and a thin plate 73 (Fig. 3) which is adapted to be secured to the sides of revolving cylinder 7 (to confine a heat insulating medium) form no part of my present invention. 90

As will be understood the engine may be operated singly or in a series in conjunction with a condenser or otherwise. With suitable alterations of the ports of valve 52 the engine may be adapted to operate as a 95 pump.

Having described my invention, what I claim as new and desire to secure by Letters Patent, is—

1. In a rotary engine; in combination, a 100 bed-plate provided with a cam-ring, and upright stands; a ported, hollow, stationary, shaft or cylinder; a tapered, ported, valve therein; removable inlet and exhaust heads, secured to said hollow shaft or cylinder, and 105 supported on the upright stands; a revolving cylinder, mounted on said hollow shaft or cylinder on bearing sleeves, and having a collar, and vane or abutment, on said hollow shaft or cylinder, inclosed therein; diametrically opposite, radial, oscillating pistons, 110 mounted in the revolving cylinder, with retaining sleeves; cranks, having rollers, and mounted on the pistons; the rollers, adapted to be controlled by the cam-ring; the cam-ring, adapted to control the movement and oscillations of the pistons; and adjusting, and securing means, for the different parts; substantially as herein shown and described 115

2. In a rotary engine of the class described, a ported hollow stationary shaft; whereon, a revolving cylinder formed in two parts bolted together, and provided with radial oscillatory slotted pistons, is adapted, 120 to rotate on tapered bearing sleeves provided thereon; the said hollow ported shaft having, an inlet and an exhaust head secured thereto; a tapered ported valve seated in a projecting centrally located tapered valve-seat formed therein; a projecting collar formed thereon 125

having a spherical periphery, from which centrally between the edges thereof a vane or abutment projects, which is adapted, to fit closely to spaced apart walls of the said revolving cylinder, which spaced apart walls, form circular cavities wherein the said projecting collar and vane or abutment is included when the said revolving cylinder is mounted to rotate on tapered bearing sleeves 5 provided on the said ported hollow shaft, and whereby when so mounted, an annular working chamber is formed in the said revolving cylinder into which the said vane or abutment projects; short inclines formed 10 thereon next each side of the said projecting collar; ports, formed at each radial edge of the said vane or abutment through the said projecting collar and tapered valve-seat, and adapted to be in communication with the 15 said annular working chamber and the ports formed in the said tapered valve; and an oil duct formed therein; substantially as herein shown and described.

3. In a rotary engine of the class described, the combination comprising, the revolving cylinder formed in two parts, which is provided with the diametrically opposite radial oscillatory slotted pistons, and is mounted on the ported hollow shaft to rotate 20 on tapered bearing sleeves provided thereon, and wherein the projecting collar, provided with a spherical periphery, and the vane or abutment formed on said shaft, are included; an inlet and an exhaust head 25 secured to the said ported hollow shaft, and the said heads mounted on the flanged seats provided on the upright stands, which stands are secured on the bed-plate which is also provided with a cam-ring wherein a cam- 30 path is formed, and which cam-ring is held concentric with the said revolving cylinder, the said oscillatory slotted pistons being provided with cranks whereon rollers are 35 mounted; the said rollers projecting into the said cam-path and being adapted to travel therein; the said cam-path adapted to control the oscillations of the said oscillatory pistons, so that same may pass the said vane or abutment when the said oscillatory 40 pistons travel below a horizontal plane, which passes through the axis of the said ported hollow shaft, and so that said oscillatory pistons form fluid tight abutment walls within the working chamber of the 45 said revolving cylinder when same travel above the said horizontal plane; the said inlet and exhaust heads adapted to support a pipe thereon which may communicate with the bore of the said ported shaft through a 50 passage formed in the said heads; a stuffing-box formed on the said inlet head; a removable cover provided on the exhaust head; and means whereby the said heads 55 may be secured and adjusted side and end- wise on the flanged seats provided on the

said upright stands; substantially as herein shown and described.

4. In a rotary engine; the tapered valve, provided with a central hole, and having an expanding inlet and two exhaust ports 70 formed in the tapered periphery thereof, these ports adapted to form part of the passage for the actuating fluid from the inlet into the exhaust end of the ported, hollow, stationary, shaft, or cylinder, the inlet port 75 in conjunction with the valve-seat forming an expanding passage, in which the actuating fluid is expanded, substantially as herein shown and described and for the purpose specified.

5. In a rotary engine; the combination with the ported, hollow, stationary, shaft or cylinder, provided with the removable inlet and exhaust heads, and having the collar, and vane or abutment, on the outside thereof, and the tapered valve-seat on the inside, and ports at each radial edge of the vane or abutment, through the collar, shaft, and valve-seat, of the tapered valve, (having an expanding inlet port and two exhaust ports) 90 seated in the valve-seat, the round rod mounted in the valve extending through a stuffing box bearing, the stuffing box, formed on the inlet head, the lever mounted on said rod in contact with the gland of the stuffing 95 box, means, adapted to hold the valve fluid tight in its seat, and means securing the lever to the rod, and adapted to rotate the rod and the valve, whereby the inlet or an exhaust port may be stationed at either port 100 through the collar, shaft, and valve-seat, the exhaust head provided with an opening through which the valve is adapted to pass, said opening closed fluid tight by a cover, and means, securing the cover to said head, 105 substantially as herein shown and described and for the purpose specified.

6. In a rotary engine of the class described, a revolving cylinder which is provided with diametrically opposite, radial, 110 oscillatory, slotted pistons, and is adapted to be mounted on a ported hollow shaft, to rotate on tapered bearing sleeves provided thereon; the said revolving cylinder being formed in two parts which are provided 115 with hubs having a tapered bore; outer flanges formed thereon through which said parts are bolted together; spaced apart walls which form circular cavities identical in each part, and which spaced apart walls, are 120 adapted, to fit closely to a projecting collar having a spherical periphery and a vane or abutment projecting therefrom, which are formed on the said ported hollow shaft, and which are included in the said circular cavities when the said revolving cylinder is mounted on the said hollow ported shaft, to 125 rotate on tapered bearing sleeves provided thereon, and whereby when so mounted, an annular working chamber is formed in the 130

said revolving cylinder into which the said vane or abutment projects, the said annular working chamber being then in communication with the bore of the said hollow shaft, 5 by means of ports formed therein at each radial edge of the said vane or abutment; diametrically opposite enlargements of the said spaced apart walls, forming piston seats wherein the said oscillatory pistons are 10 mounted, the axis of the said seats being located on a radial line in the central perpendicular plane of the revolving cylinder; flanges formed at the outer end of the piston seats, and through which, flanged retaining 15 sleeves, adapted to retain the oscillatory pistons in said seats, are secured to the said revolving cylinder; substantially as herein shown and described.

7. In a rotary engine; the combination 20 with the ported, hollow, stationary, shaft or cylinder, with the revolving cylinder mounted on said hollow shaft or cylinder, and having the collar provided with a spherical periphery, and vane or abutment thereof included therein, the spherical periphery of the collar forming the inner wall of an annular chamber, into which the vane or abutment projects and which with the radial edges of the vane or abutment forms the 25 stationary boundaries of said chamber, substantially as herein shown and described.

8. In a rotary engine; the combination 30 with the oscillating pistons, having diametrically opposite wings connected together, a central slot between the wings, and the end of the wings concaved, and having a round stem provided with a square seat, of the cranks, provided with a roller, mounted on the square seat of said stem in an angular position 35 with said slot, the angle being half the throw or oscillation of the piston, substantially as herein shown and described.

9. In a rotary engine; the combination 45 with the revolving cylinder, and the collar and vane or abutment, of the ported, stationary, hollow, shaft or cylinder included therein, of the oscillating pistons, provided with the cranks and rollers, and having diametrically opposite wings connected together 50 and provided with concaved ends, with a central slot between the wings, mounted in the radial seats of the revolving cylinder, and adapted to rotate therein, with the concaved ends of the wings in continuous contact 55 with the spherical periphery of the collar, the axis of oscillation being in the central perpendicular plane of the collar, and the diameter of the pistons being equal to the width of the collar, substantially as herein shown and described.

10. In a rotary engine provided with a revolving cylinder having radial oscillatory pistons; the retaining sleeves, connected by threaded shoulders, and gland adapted 60 to project between the walls thereof, the

outer sleeve and gland having a flange, adapted to be secured to the revolving cylinder, the inner sleeve having a central hole through which a round stem of the pistons is adapted to pass, and the inner sleeve adapted 70 to rotate in the outer sleeve, and means, to rotate said sleeve, substantially as herein shown and described.

11. In a rotary engine; the combination 75 with the revolving cylinder, having the collar and vane or abutment provided on the ported, hollow, stationary, shaft or cylinder and included therein, and the oscillating pistons, provided with the cranks and rollers mounted in the radial seats of the revolving 80 cylinder, of the retaining sleeves provided with threaded shoulders, mounted in the extension of the radial piston seats, the outer sleeves secured to the revolving cylinder, the inner sleeves adapted to rotate in the 85 outer sleeves, and having the stem of the pistons passing through the central hole, and adapted by the threaded shoulders to adjust the oscillating pistons endwise in the radial seats, and the flanged glands secured 90 to the revolving cylinder between the sleeves, substantially as herein shown and described and for the purpose specified.

12. In a rotary engine; the combination 95 with the revolving cylinder, having diametrically opposite oscillating pistons, held by retaining sleeves, and having hubs with a tapered bore, and mounted on a ported, hollow, stationary, shaft or cylinder, provided with a collar and vane or abutment said 100 collar and vane or abutment thereof being included therein, the short inclines on said hollow shaft or cylinder, and the lugs on the inlet and exhaust heads, secured to said hollow, shaft or cylinder, of the 105 tapered bearing sleeves, mounted slidably on said hollow, shaft or cylinder, and projecting into the tapered bore of the hubs on which the revolving cylinder is adapted to rotate, the sleeves forced on the short inclines on said hollow, shaft or cylinder, by means, in conjunction with lugs on the tapered bearing sleeves, and lugs on the inlet and exhaust heads secured to said hollow, 110 shaft or cylinder, whereby the tapered bearing sleeves are held adjustably endwise, substantially as herein shown and described and for the purpose specified.

13. In a rotary engine; the combination 115 with the cam-ring secured on the bed-plate, 120 of the revolving cylinder, mounted on bearing sleeves on a ported, hollow, stationary, shaft or cylinder provided with a collar and vane or abutment, said collar and vane or abutment thereof being included therein, the 125 hollow, stationary, shaft or cylinder, with the inlet and exhaust heads secured thereto, supported on the upright stands, the revolving cylinder held concentric with the cam-ring, and with the central vertical plane of 130

said cylinder in a central plane between the vertical planes of the parallel straight portions of the cam-ring, and of the oscillating pistons, provided with the cranks and rollers 5 and mounted in the diametrically opposite radial seats of the revolving cylinder, and held rotably therein by the retaining sleeves, secured to the revolving cylinder, the rollers adapted to project into the cam-path of the 10 cam-ring and travel therein, and oscillate the pistons controlled by the cam-path of the cam-ring, the pistons being oscillated into the open and closed position as required when rotating with the revolving cylinder, substantially as herein shown and described 15 and for the purpose specified.

14. The combination with a rotary engine of the kind in the working chamber or working chambers of which, a stationary 20 abutment or the equivalent thereof co-operates with rotating piston abutments, to form fluid tight compartments in the said working chamber or working chambers, and which piston abutments are adapted while 25 rotating with the rotor element of the engine, to pass the said stationary abutment or the equivalent thereof, and to then be propelled therefrom toward the exhaust opening of the said working chamber or 30 working chambers, by the pressure then exerted thereon by an actuating fluid, which

is admitted into the said working chamber or working chambers through an inlet opening thereof, and whereby rotation of the rotor element of the engine is effected; of 35 means adapted to form a suitable fluid expanding passage or nozzle, having a throat formed therein, from which throat the said expanding passage or nozzle is formed to have a gradually increasing cross-sectional 40 area, and which expanding passage or nozzle preferably terminates at, and is held in fluid tight communication with, the inlet opening of the said working chamber or working chambers of the said engine; the 45 said means adapted to be connected to means forming a passage through which an actuating fluid under pressure may flow and be conducted thereby into the said working chamber or working chambers of the said 50 engine; substantially as herein shown and described and as may be variously carried out in accordance herewith for the purposes set forth.

In testimony whereof I have signed my 55 name to this specification in the presence of two subscribing witnesses.

WILLIAM C. F. BRUEGEMANN.
